EXHIBITING EGG HATCHER

Walter A. Ketay, Huntington, N. Y.

Application April 14, 1947, Serial No. 138,378

Term of patent 14 years

(Cl. D80—11)

To all whom it may concern:

Be it known that I, Walter A. Ketay, a citizen of the United States, residing in Huntington, in the county of Suffolk and State of New York, have invented a new, original and ornamental Design for an Exhibiting Egg Hatcher, of which the following is a specification, reference being had to the accompanying drawing, forming a part hereof, in which:

Fig. 1 is a perspective view from one corner of an exhibiting egg hatcher, showing my new design;

Fig. 2 is a perspective view taken from the opposite corner thereof; and

Fig. 3 is a top plan view of the exhibiting egg hatcher with the transparent cover removed for convenience of illustration.

I claim:

The ornamental design for an exhibiting egg hatcher, substantially as shown.

WALTER A. KETAY.
